UNITED STATES PATENT OFFICE.

ISAAC E. PALMER, OF MIDDLETOWN, CONNECTICUT.

DESIGN FOR A HAMMOCK-BODY.

SPECIFICATION forming part of Design No. 35,046, dated September 3, 1901.

Application filed August 10, 1901. Serial No. 71,658. Term of patent 14 years.

To all whom it may concern:

Be it known that I, ISAAC E. PALMER, a citizen of the United States, and a resident of Middletown, in the county of Middlesex and State of Connecticut, have invented and produced a new and useful original Design for a Hammock-Body, of which the following is a specification.

The essential feature of my design consists in a hammock-body comprising a central portion and border portions differentiated from the central portion, the border portions being embellished with T-shaped figures alternately reversed.

15 The accompanying drawing represents an end view of the body of the hammock.

The central portion is denoted by *a*, the border portions differentiated from the central portion are denoted by *b*, and the reverse T-shaped figures which embellish the border portions are denoted by *c*.

What I claim is—

The design for a hammock-body substantially as herein shown and described.

In testimony that I claim the foregoing as my invention I have signed my name, in presence of two witnesses, this 11th day of July, 1901.

ISAAC E. PALMER.
